SEALING SHOE FOR FLOATING DECKS

Andrew A. Kramer, Kansas City, Mo., assignor
to George D. Beardsley, Kansas City, Mo.

Application March 18, 1932, Serial No. 599,721

5 Claims. (Cl. 220—26)

My invention relates to sealing means for floating decks, and more particularly to sealing shoes for floating decks.

In oil storage tanks floating roofs or decks are frequently used and have many advantages which are well known. In such devices the floating deck is made smaller in diameter than the tank, and the intervening space between the deck and tank must be sealed against the escape of vapors from the surface of the oil or other liquid in the tank, and from the admission of air into the space in which the liquid is contained. Such sealing means must be flexible so that the same can expand and contract in accordance with the variations in the contour of the tank, and usually comprises metallic members engaging the side wall of the tank so that said metallic members slide up and down on said side wall as the floating deck changes its position due to the change in level of the oil. Sealing means of this character are shown in the patent to Andrew A. Kramer #1,767,142 patented June 24, 1930, and the patent to Frederich W. Kueffer #1,765,593 patented June 24, 1930, and the present invention is an improvement on the sealing means shown in said patents.

It is a purpose of my invention to provide new and improved sealing means for a floating deck comprising such sealing members or shoes and means for sealing the gaps between the adjoining shoes to provide a gas tight seal for the floating deck.

More particularly, it is a purpose of my invention to provide sealing shoes for a floating deck, which have strips of gas tight flexible material secured thereto so that said strips of material are fixed relative to one of said shoes and are in slidable engagement with the surface of the next adjoining shoe. In the preferred arrangement, the flexible sealing members are secured to one shoe at each joint and overlap the adjacent shoe at each joint.

It is a further purpose of my invention to provide new and improved sealing means for tanks provided with floating decks comprising metallic shoes or sealing plates, which are provided with offset portions to accommodate the flexible sealing material, which overlaps the joints between adjacent shoes to substantially align the surface of the flexible sealing material overlapping the joints with the body portions of the shoes so as to provide a better seal between the shoes and the tank wall, while at the same time providing a vapor or gas tight seal for the joints between the metallic shoes.

It is a particular purpose of my invention to

provide a sealing means for a floating deck comprising shoes swingingly mounted on the floating deck and engaging with the side wall of the tank, said shoes carrying sealing material which hold said shoes in engagement with said side wall by the action of gravity, said shoes being curved and having the convex surfaces thereof contacting with the tank wall and being provided with flexible sealing members overlapping the joints between said shoes, said flexible sealing members being provided on the convex faces of the shoes.

While it is desirable and necessary that the sealing material be provided on the convex faces of the shoes, it is not absolutely necessary that such sealing material be provided on the concave face thereof, but such sometimes is desirable to obtain a perfect seal between the adjacent sealing shoes.

Other objects and advantages of my invention will appear as the description of the drawing proceeds. I desire to have it understood, however, that I do not intend to limit myself to the particular structure shown and described, except as defined in the claims.

In the drawing:

Fig. 1 is a fragmentary vertical sectional view through a portion of a tank and floating deck and the sealing means associated therewith, embodying my invention.

Fig. 2 is a fragmentary circumferential sectional view through a sealing shoe and portions of the shoes on each side thereof.

Fig. 3 is a fragmentary face view of the sealing shoes as viewed from the inner face of the side wall of the tank substantially on the line 3—3 of Fig. 1, the middle portion of said sealing shoes being broken away.

Fig. 4 is an enlarged fragmentary sectional view through the joint between adjacent sealing shoes, and

Fig. 5 is a view similar to Fig. 4 of a modification.

Referring in detail to the drawing, my improved sealing shoes are shown in Fig. 1 as being provided in a tank having a side wall 10 and on a floating deck 11, having an inwardly and upwardly inclined peripheral flange 12 thereon, and provided with a depending rim portion 13, which has an outwardly directed flange 14 provided with slots through which the ears 15 on the metallic shoes 16 extend. The shoes 16 are curved to provide a convex outer face thereon contacting with the inner face of said side wall 10 of the tank and a concave inner face. Said shoes are pro-

vided with rain shedding members 17 secured to the upper ends thereof and carry basket members 18 in which gas tight sealing fabric 19 and loose sealing material 20 is provided, the sealing material 20 being made up of gravel, small crushed stone, sand or any similar material as may be found desirable, and due to its weight, serves to hold the sealing shoes 16 in sliding contact with the side wall 10 of the tank.

10 The liquid level in the tank is indicated at 21 in the drawing, and while the sealing material 19 and 20 will substantially prevent the escape of gases or vapors from the space between the shoes 16 and the inwardly sloping wall 12 on the floating deck 11, such vapors or gases can escape at the joints between the sealing shoes 16 unless the same are properly sealed.

My improved sealing shoes prevent the escape of such vapors or gases that would not be stopped 20 by the sealing material 19 and 20 from between the sealing shoes at their adjoining side edges. In order that such sealing means will function properly it is necessary that it be free to accommodate itself to the different positions that the 25 shoes assume and still maintain the seal between the adjoining shoes. The sealing shoes 16 move into various angular positions about their pivotal axes in the slots in the flange 14 as the distance between the side wall 10 of the tank and the deck 30 11 varies. The point of contact between the shoes 16 and the side wall 10 varies according to such angular position, and the structure of the shoes and of the joint sealing means associated with the adjoining sealing shoes is so constructed as to accomplish this purpose without preventing good sealing contact between the shoes and the side wall of the tank. In order to accomplish such sealing of the joints between adjacent shoes without interfering with their sealing action in cooperation with the side wall 40 of the tank, the side edges of the shoes 16 are offset inwardly toward the concave face thereof or toward the floating deck, the inwardly offset portion at one side edge of each shoe being indicated by the numeral 22, and that at the other side edge of the shoe being indicated by the numeral 23.

In the form of the invention shown in Figs. 1, 2, 3 and 4 said shoes are further provided with inwardly directed flanges 24, which will prevent 50 one shoe 16 from overriding the edge of the adjoining shoe 16. Secured to the offset portion 23 of each shoe 16 by any suitable securing means, such as the rivets 25, are the strips 26 of flexible 55 sealing material. The sealing members 26 overlap the offset portion 22 of the next adjacent sealing shoe 16, and are preferably made of a fabric or fibrous material that is impregnated with a suitable substance to form a gas tight and oil 60 proof flexible fabric. Due to the fact that the flexible gas tight and oil proof sealing members 26 are carried in the shallow grooves formed by the offset portions 22 and 23 of the members 16 and lie between said members and the side wall 65 10 of the tank, these will be held in sealing contact with the offset portions 22 of the shoes, as well as the offset portions 23 thereof, and will be free to slide over the portions 22. The flexible sealing members are made up of a fabric material 70 that has sufficient stiffness that the same will tend to hug the offset portions 22 of the adjacent sealing member 16 closely throughout the length of the offset portions 22 in spite of the convex character of the sealing member 16, because of 75 the firm securing of said flexible members 26

to the offset portions 23 of the sealing shoes 16 that carry the same.

While the arrangement described above provides a tight seal in most cases, it may be desirable in order to obtain an absolutely perfect seal that the arrangement shown in Fig. 5 be provided in which the shoes 16' are made in the same manner as the shoes 16, except that the offset portions 22' and 23' thereon are not provided with any flanges, such as shown in Fig. 4, and have 10 not only the flexible members 26 secured to the flanges 23' by the securing members 25, but also similar flexible members 26', which overlie the concave faces of the offset portions 23' and 22' of the shoes 16' in the same manner that the 15 flexible members 26 overlie the convex faces of said offset portion, thus providing a double seal at each of the joints at the side edges of the sealing shoes.

What I claim is:—

1. The combination with a floating deck and a tank, of shoes mounted on said deck and engaging the side wall of said tank, said shoes lying side by side adjacent each other in slightly spaced relation and means for sealing the joint between the side edges of adjacent shoes comprising flexible gasket members secured to only one of said shoes at each of said joints and overlapping the other shoe at said joint and being freely slidable thereon, said gasket members engaging the faces of said shoes toward said tank side wall to seal the joint between said shoes and said side wall also.

2. The combination with a floating deck and a tank, of shoes mounted on said deck and engaging the side wall of said tank, said shoes lying side by side adjacent each other in slightly spaced relation and means for sealing the joint between the side edges of adjacent shoes comprising flexible gasket members secured to only one of said 40 shoes at each of said joints and overlapping the other shoe at said joint and being freely slidable thereon, said gasket members engaging the opposite faces of said shoes, and one thereof lying between said shoes and the side wall of said tank. 45

3. The combination with a floating deck and a tank, of shoes mounted on said deck and engaging the side wall of said tank, said shoes lying side by side adjacent each other in slightly spaced relation, and each having both marginal portions 50 thereof adjacent the side edges thereof offset inwardly toward said deck and flexible fabric sealing means engaging the offset portions of said shoes face to face on the faces thereof toward said tank side wall and bridging the joints between adjacent shoes to seal the joints between adjacent shoes and the joints between said shoes and the side wall of said tank at said offset portions.

4. The combination with a floating deck and a tank, of curved metallic shoes swingingly mounted side by side on said deck in slightly spaced relation and having the convex faces thereof engaging said tank side wall, and means for sealing the joints between adjacent shoes comprising members of flexible gas tight sheet material overlapping said joints on the convex faces of said shoes, said shoes being offset on both adjacent edges thereof to provide shallow recesses in the convex faces thereof to accommodate said sealing members, said sealing members engaging said side wall to provide a seal between said shoes and said side wall at said recesses, said gas-tight material being substantially flush with the tank engaging faces of said shoes.

5. The combination with a floating deck and a tank, of shoes mounted on said deck and engaging the side wall of said tank, said shoes lying side by side adjacent each other in slightly spaced relation and means for sealing the joint between the side edges of adjacent shoes, comprising flexible gasket members secured to one of said shoes

at each of said joints and overlapping the other shoe at said joint and being freely slideable thereon, said flexible members engaging the faces of said shoes directed toward said tank side wall and said shoes having means thereon to limit the movement thereof toward each other. 5

ANDREW A. KRAMER.
